UNITED STATES PATENT OFFICE.

MELVIN D. MORTON, OF GAULEY MILLS, WEST VIRGINIA.

CIRCUIT-CLOSER FOR COMBINATION-LOCKS AND BURGLAR-ALARMS.

1,249,992.

Specification of Letters Patent. Patented Dec. 11, 1917.

Application filed June 6, 1916. Serial No. 101,942.

To all whom it may concern:

Be it known that I, MELVIN D. MORTON, a citizen of the United States, residing at Gauley Mills, in the county of Webster and 5 State of West Virginia, have invented certain new and useful Improvements in Circuit - Closers for Combination - Locks and Burglar-Alarms; and I do hereby declare the following to be a full, clear, and exact 10 description of the invention, such as will enable others skilled in the art to which it appertains to make and use the same.

This invention relates to a combination lock and burglar alarm and more particularly to a device adapted to be attached or 15 made integral with any type of lock employing a locking bolt, whereby it will be necessary to operate the combination before the key to the lock can be inserted within the 20 lock.

An object of this invention is to provide a cylindrical barrel attached or made integral to the front wall of the casing of a lock and covering the keyhole therein and 25 having a plurality of sector plates pivotally mounted in the barrel and in alinement with the keyhole of the lock, whereby said plates will have to be moved in such a manner to allow a key to be inserted through the barrel 30 into the lock, for operating the lock mechanism.

Another object of this invention is to provide a pair of blocks, each one of which is pivoted to the barrel upon each side of 35 the sector plates, so that when any one of the sector plates is moved in a wrong or incorrect direction, the blocks will be swung upon their pivots and close an electric circuit to an alarm, notifying that the lock is 40 being tampered with by an unauthorized person who is not familiar with the combination.

A further object of this invention is the provision of a combination lock and burglar 45 alarm of the above stated character which shall be simple, durable and efficient, and which may be manufactured and sold at a comparatively low cost.

With these and other objects in view as 50 will become more apparent as the description proceeds, the invention consists in certain novel features of construction, combination and arrangement of parts as will be hereinafter more fully described and 55 claimed.

For a complete understanding of my in-

vention, reference is to be had to the following description and accompanying drawings, in which:—

Figure 1 is a front elevation, partly in 60 section of a combination lock and a burglar alarm, constructed in accordance with my invention,

Fig. 2 is a longitudinal sectional view, 65 taken on the line 2—2 of Fig. 1, illustrating the means of connecting the sector plates with the lock,

Fig. 3 is a similar view taken on the line 70 2—2 of Fig. 1, illustrating a key passing through the sector plates,

Fig. 4 is a vertical sectional view illustrating a means attached to the pivoted lock and barrel for closing an electric circuit to an alarm, and

Fig. 5 is a detail view illustrating a portion 75 of a lock.

Referring in detail to the drawings, the numeral 1 indicates a cylindrical barrel, which may be secured or made integral to a lock casing 2, that may be of any construction or 80 formation, but to better illustrate my invention I have shown a lock consisting of a sliding bolt 3 which is adapted to be normally held into engagement with a keeper by means of a coil spring 4 positioned between the inner end of the sliding bolt 3 and the wall of the casing 2. The front wall of the casing 2 is provided with the ordinary keyhole plate 5 having formed thereon a lug 6. The lug 6 is adapted to engage a notch 90 7 in the sliding bolt 3 for drawing the sliding bolt 3 within the casing 2, to free the bolt from the keeper (not shown), the keyhole plate 5 being operated by a key which will be hereinafter more fully described. 95

The cylindrical barrel 1 is provided with a front wall 8 which is provided with an opening 9, the opening 9 being closed by a circular plate 10 positioned upon the inner face of the front wall 8 and held thereto by means of an angular ring 11 bolted or otherwise secured to the front wall 8, providing an angular recess for the circular plate 10 to rotate in. The circular plate 10 100 is provided with a keyhole 12 adjacent one edge thereof to receive the key heretofore mentioned.

A longitudinal extending shaft 13 is journaled in the front wall of the lock casing 2 110 and in the front wall 8 of the cylindrical barrel 1 and has mounted thereon sector plates

14, 15, 16, 17 and 18, each of which have a downwardly depending arm 19 that is secured to coil springs 20 by means of eye-bolts 21. The coil springs 20 are secured to 5 the barrel 1 by suitable eye-bolts 22, providing means for normally holding the sector plates vertically within the cylindrical barrel 1. The sector plates are provided with slots 23 and 24, which slots are arranged 10 within the curved ends of the sector plates and adjacent the straight edges thereof. Formed on each of the sector plates are upwardly extending lugs 25, having operating rods 26 pivotally secured thereto, the ends 15 of which are bent at right angles to form hooks 27.

A pair of blocks 27 and 28 are provided with extensions 29 at each end thereof and are journaled in the front wall of the casing 20 2 of the lock and the front wall 8 of the cylindrical barrel and arranged upon each side of the sector plates. Each of the blocks 27 and 28 is provided with a plurality of notches 30 and being divided by wires 31. 25 The operating rod 26 which is pivotally secured to the sector plates 14 is positioned within one of the notches 30 of the block 28 and the hooked end 27' engages the wire 31, to provide a connection between the sector 30 plate 14 and the block 28, which will swing the block 28 upon its pivot when the sector plate 14 is moved to the left. The operating rod 26 which is secured to the sector plate 15 extends into one of the notches of the 35 block 27 and is provided with its hooked end 27' in an engagement with the wire 31, to provide a connection between the sector plate 15 and the block 27, which will cause said block 27 to swing upon its pivot when 40 the sector plate 15 is moved to the right. The operating rod 26 which is pivotally secured to the sector plate 16 extends into one of the notches 30 of the block 28 and its hooked end 27' engages the wire 31, to provide 45 a connection between the sector plate 16 and the block 28, which will cause said block 28 to swing upon its pivot and the sector plate 16 is moved to the left. The operating rod 26 which is connected to the 50 sector plate 17 extends into one of the notches 30 of the block 27 and its hooked end 27' engages the wire 31 and provides a connection between the sector plate 17 and the block 27 which will cause said block 27 55 to swing upon its pivot when the sector plate 17 is moved to the right. The operating rod 26 which is pivotally secured to the sector plate 18 engages one of the notches 30 of the block 28 and its hooked 60 end 27' engages the wire 31 and provides a connection between the sector plate 18 and the block 28, which will cause the block 28 to swing upon its pivot when the sector plate 18 is moved to the left. The blocks 65 27 and 28 are normally held in a substan-

tially vertical position as illustrated in Fig. 1 by means of coil springs 32 and 33, which are secured to the cylindrical barrel 1. The slot 23 in the sector plate 14, the slot 24 in the sector plate 15, the slot 23 in the sector plate 16, the slot 24 in the sector plate 17 and the slot 23 in the sector plate 18 are each provided with communicating recesses 34, for receiving a portion of the key, which will be hereinafter more fully described. 70 75

The key 35 consists of a shank having a plurality of relatively spaced bits 36 formed thereon. The key is inserted through the opening 12 that is adjacent one edge of the circular plate 10 and turning the key, the plate 10 is rotated and the key moves in the direction of the slot 23 and is then inserted far enough to position its first bit in the slot 23 of the sector plate 14, after which the key is moved to the right to align the slot 23 of 80 the sector plate 14 with the slot 24 of the sector plate 15, then the first bit is shoved into the slot 24 of the sector plate 15, permitting the second bit to occupy the slot 23 of the sector plate 14. When the sector plate 14 is thus swung, the operating rod 26 is pushed in the direction of the block 28 and the operating rod 26 slides freely through the notch 30 of the block 28 and does not swing said block 28 upon its pivot. After 85 the key has been inserted into the slot 24, of the sector plate 15, the key is moved to the left, causing the sector plates 14 and 15 to move in a corresponding direction by the first and second bits, and then the first bit 90 is pushed into the slot 23 of the sector plate 16. The operating rod 26 which is connected with the sector plate 15 and to the block 27 will allow said sector plate to move to the left without moving said block 27 95 upon its pivot. After the key has been inserted through the slot 23 in the sector plate 16, the key is moved then to the right and pushed through the slot 24 in the sector plate 17. The key is then again moved to 100 the left so that it may be inserted in the slot 23 in the sector plate 18. When the key has been successfully passed through the slots of the various sector plates, it then may be pushed into the key plate 5 of the lock 2 so 105 that said key plate 5 may be rotated to withdraw the bolt 3 from the keeper (not shown). After the key has been inserted in the key plate 5, the bits thereof are positioned in the communicating recesses 34 of 110 the respective sector plates, whereby the key may be rotated to operate the bolt 3 without moving or influencing the sector plates. The bits of the key when in the recesses of the sector plates will permit only slight movement of said sector plates, which is not sufficient to actuate the blocks. 115 120

Each of the blocks 27 and 28 is provided at one of their ends with a contact pole 37 which is insulated from the respective blocks 125 130

to which it is secured and poles 39 are secured to the front wall 8 of the barrel 1 adjacent each block 27 and 28 and are provided with their free ends bent to form a catch for engaging the pole 37 carried by the blocks 27 and 28 when said blocks are rocked upon their pivot to close an electric circuit to conductors 40 and 41 which are connected respectively to the pole 37 and the pole 39 and are connected with a suitable electric circuit (not shown) for sounding an alarm when the blocks 27 and 28 are swung upon their pivots.

If a person not familiar with the correct combination of this lock, endeavors to open the lock by inserting the key into the barrel 1 and through the sector plates, he is liable to get the key in the wrong notch of the respective sector plates, and if so and by moving the key to bring it in line with one of the notches to the next adjacent sector plate will cause the operating rod 26 which is pivoted to the sector plate which the key is passed through the incorrect notch to pull upon the respective block to which it is secured and swing it upon its pivot bringing the contact pole 37 carried thereby in contact with the contact pole 39 adjacent thereto and close the circuit to an electric alarm, which will immediately notify that the lock is being tampered with. If the person is successful in getting the key through the proper notch in the first sector plate, he is liable to become confused when inserting the key through the next adjacent sector plate and if so and the key is inserted in the next adjacent sector plate, the second mentioned sector plate will move the respective block to which it is connected by the operating rod 26 and swing said block upon its pivot and close the circuit to the pole 37 carried by said block and the pole 39 adjacent thereto and sound the alarm.

While I have shown and described the preferred embodiment of my invention, it will be understood that minor changes in construction, combination and arrangement of parts may be made without departing from the spirit and scope of the invention as claimed.

Having thus described my invention, what I claim is:—

1. A combination lock and burglar alarm comprising a lock casing, a spring pressed bolt slidably mounted in said casing, a barrel secured on said casing and surrounding the key hole thereto, combination means mounted in said barrel and adapted to be correctly operated before a key can be inserted within the lock casing, and means operatively connected with the combination means to close a circuit adapted to sound an alarm when the combination means is incorrectly operated.

2. A combination lock and burglar alarm comprising a lock casing, a spring pressed

bolt slidably mounted in said casing, a barrel secured on said casing and surrounding the key hole thereof, a front wall secured to said barrel and provided with an opening therein, a circular plate closing the opening and provided with a key hole therein, combination means mounted in said barrel and adapted to be correctly operated before a key can be inserted within the lock casing, and means operatively connected with the combination means to close a circuit adapted to sound an alarm when the combination means is incorrectly operated.

3. A combination lock and burglar alarm comprising a lock casing, a spring pressed bolt slidably mounted in said casing, a barrel secured on said casing and surrounding the key hole thereof, a front wall secured to the barrel and provided with a circular opening therein, a circular plate slidably mounted on the front wall of the barrel and provided with a key hole therein, a combination means mounted in said barrel and adapted to be correctly operated before the key can be inserted within the lock casing, and means operatively connected with the combination means to close a circuit adapted to sound an alarm when the combination means is incorrectly operated.

4. A combination lock and burglar alarm comprising a lock casing, a spring pressed bolt slidably mounted in said casing, a cylindrical barrel secured to the casing and surrounding the keyhole therein, a front wall secured to the barrel and provided with a circular opening therein, an annular ring detachably secured to the front wall and surrounding the opening therein to provide an annular recess, a circular plate rotatably mounted within the recess and provided with a keyhole therein, combination means mounted in said barrel and adapted to be correctly operated before a key can be inserted within the lock casing, and means to close a circuit adapted to sound an alarm when the combination means is incorrectly operated.

5. A combination lock and burglar alarm comprising a lock casing, a spring pressed bolt slidably mounted in said casing, a barrel secured to said casing and surrounding the keyhole thereof, sector plates journaled in said barrel and adapted to be correctly operated by a key before said key can be inserted within the keyhole of the casing, and means to close a circuit adapted to sound an alarm when the sector plates are incorrectly operated.

6. A combination lock and burglar alarm comprising a lock casing, a spring pressed bolt slidably mounted in said casing, a barrel secured to said casing and surrounding the keyhole thereof, a plurality of sector plates journaled in said barrel and each provided with oppositely disposed slots one of

which is adapted to receive a key to correctly operate the sector plates so that said key may be inserted within the keyhole of the lock casing, and means to close a circuit adapted to sound an alarm when the sector plates are incorrectly operated.

7. A combination lock and burglar alarm comprising a lock casing, a spring pressed bolt slidably mounted in the casing, a cylindrical barrel secured to said casing and surrounding the keyhole thereof, a plurality of sector plates pivotally mounted in said barrel and each provided with oppositely disposed slots, one of said slots of each sector plate adapted to receive a key to correctly align the sector plates before said key can be inserted into the keyhole of the lock casing, means secured to each of the sector plates for holding said sector plates in a vertical position within the barrel, and means to close a circuit adapted to sound an alarm when the sector plates are incorrectly operated.

8. A combination lock and burglar alarm comprising a lock casing, a spring pressed bolt slidably mounted in said casing, a barrel secured to said casing and surrounding the keyhole thereof, a plurality of sector plates journaled in said casing and provided with slots therein, an arm formed on each of the sector plates, springs connected to the arm and to the barrel for holding said sector plates in a vertical position, and means to close a circuit adapted to sound an alarm when the sector plates are incorrectly operated.

9. A combination lock and burglar alarm comprising a lock casing provided with a keyhole therein, a spring pressed bolt slidably mounted in said casing, a barrel secured to said casing and surrounding the keyhole thereof, a longitudinally extending shaft journaled in the barrel and lock casing, sector plates secured to said shaft and provided with slots therein, arms formed on said sector plates and depending downwardly therefrom, springs secured to the arms and to the barrel for holding said sector plates in a vertical position within the barrel, and means to close a circuit adapted to sound an alarm when the sector plates are incorrectly operated.

10. A combination lock and burglar alarm comprising a lock casing, a spring pressed bolt slidably mounted in said casing, a barrel secured to said casing, sector plates journaled in said barrel, means secured to the sector plates and to the barrel for holding said sector plates in a vertical position within the barrel, blocks pivotally secured with the barrel, electrical means connected with the blocks, and means connected to the sector plates and to the block for swinging said blocks upon their pivots when the sector plates are incorrectly operated.

11. A combination lock and burglar alarm comprising a lock casing, a spring pressed bolt slidably mounted in said casing, a barrel secured to said casing, sector plates journaled in said barrel and in horizontal alignment with each other, means connected to the sector plates and to the barrel for holding said sector plates against accidental movement, spring held blocks pivotally secured within the barrel, electric contacts connected with the blocks and barrel, and means connected to the sector plates and to the block for swinging said block upon their pivots when the sector plates are incorrectly operated.

12. A combination lock and burglar alarm comprising a lock casing, a spring pressed bolt slidably mounted in said casing, a barrel secured to said casing, sector plates journaled in said barrel, means for holding said sector plates in horizontal alignment with each other, said sector plates provided with slots therein, an ear formed on each of the sector plates, spring held blocks pivoted upon each side of the sector plates, electric contacts connected with the blocks and barrel, and means connected to the ear and to the blocks for swinging said blocks upon their pivots when the sector plates are incorrectly operated.

13. A combination lock and burglar alarm comprising a lock casing, a spring pressed bolt slidably mounted in said casing, a barrel secured to said casing, sector plates journaled in said barrel, means secured to each of the sector plates for normally holding them in horizontal alignment with each other, said sector plates provided with slots therein, spring held blocks pivotally mounted within the barrel and positioned upon each side of the sector plates, electric contacts connected with the blocks and barrel, operating rods connected to each of the sector plates, one of said operating rods connected with one of the blocks and the other operating rod connected with the other block to swing either of the blocks to sound an electric alarm when any of the sector plates are incorrectly operated.

14. A combination lock and burglar alarm comprising a lock casing, a spring pressed bolt slidably mounted in said casing, a barrel secured to said casing, sector plates journaled in said casing, means for holding said sector plates in horizontal alignment with each other, spring held blocks pivotally secured within the casing and positioned upon each side of the sector plates, contact poles carried by the blocks, contact poles carried by the barrel and provided with their ends bent to form catches, means for connecting the poles in circuit with an electric alarm, said blocks provided with a plurality of notches therein, wires intersecting the notches of said blocks, and rods connected

to the sector plates and extending into the notches of the blocks and provided with their free ends bent at right angles to engage the wires within the notches of the blocks to swing said blocks to sound an electric alarm when any of the sector plates are incorrectly operated.

In testimony whereof I affix my signature in presence of two witnesses.
